J. S. Thompson,

Jointing Staves.

No 44,233.

Patented Sep. 13, 1864.

UNITED STATES PATENT OFFICE.

JOHN S. THOMPSON, OF GLENN'S FALLS, NEW YORK.

IMPROVEMENT IN STAVE-JOINTING MACHINES.

Specification forming part of Letters Patent No. 44,233, dated September 13, 1864.

To all whom it may concern:

Be it known that I, JOHN S. THOMPSON, of Glenn's Falls, in the county of Warren and State of New York, have invented a new and Improved Machine for Jointing Staves; and I do hereby declare that the following is a full, clear, and exact description thereof, which will enable those skilled in the art to make and use the same, reference being had to the accompanying drawings, forming part of this specification, in which—

Figure 1 is a side sectional view of my invention taken in the line $x x$, Fig. 2; Fig. 2, a plan or top view of the same; Fig. 3, a transverse vertical section of the same taken in the line $y y$, Fig. 1.

Similar letters of reference indicate corresponding parts.

This invention relates to a new and improved machine for jointing staves, whereby the work may be done in a very expeditious and perfect manner and with very little labor on the part of the attendant.

A represents a framing of rectangular form and constructed in any proper manner to support the working parts. On the upper parallel bars of the framing A there are secured ways or guides B B, of concave form, and upon which a carriage, C, is fitted and allowed to work freely back and forth. The curvature of the guides B correspond to the curvature or bilge designed to be given the staves.

The carriage C is composed of two transverse bars, $a a$, connected by two longitudinal bars, $b b$, and between the bars $a a$ there is fitted a frame, D, which is allowed to turn freely on journals $c c$. This frame D is provided at one side with a clamp, E, which is operated by a lever, F, with a cam, d, at its end. One end of the carriage C has a strap, G, attached to it, which passes over a pulley, e, at one end of the framing A, and has a weight, f, secured to its lower end, the opposite end of the carriage having a strap, H, attached to it, which is connected to a pulley, I, on a shaft, J, at the opposite end of the framing, said pulley I being connected to and disconnected from the shaft J by means of a clutch, K, one part of which is at one end of the pulley, the latter being moved in order to engage and disengage the clutch, which is

done by means of a shaft, L, having an upright lever, g, at one end, and an upright arm, h, at the opposite end, the upper end of said arm being forked to fit on a collar, i, on the shaft J. This shaft L also has an upright arm, j, attached to it near the arm h, the use of which will be presently shown.

M is a shaft, which is placed vertically in the framing A, and has a circular head or disk, N, on its upper end, provided with cutters k of gouge form. This cutter head or disk is at the center of the framing A, and the shaft M is driven by a belt, l, from a shaft, N^2 , at one end of the framing. The shaft J is driven by gears m from a shaft, O, which has motion communicated to it from the shaft N^2 by a belt.

P is a platform or frame, which is attached at one side to one of the side bars of the framing by means of joints or hinges o; and p p are adjustable stops attached to the opposite side bar of the framing to limit the upward adjustment of the platform or frame P. (See Fig. 3.) The platform or frame P is connected by a bar, q, with a slide, Q, fitted between guides, said slide being connected by a strap, s, with a treadle, R. The bar q is connected to the slide and platform or frame by joints t.

The operation is as follows: The staves to be jointed are fitted or placed edgewise in the carriage C, and rest upon the platform P, which is kept elevated by the foot of the attendant placed on the treadle R. This platform causes the lower edges of the staves to be brought to a proper level. The staves are then firmly secured in the frame D of the carriage by means of the clamp E. The platform is then allowed to drop by removing the foot from the treadle, and the pulley I is then, by actuating the shaft L, connected with the shaft J, and the carriage C is drawn over the cutter-head N, which cuts or joints the lower edges of the staves, the longitudinal curve or bilge being given them by the passage of the carriage over the concave ways or guides B B, and the bevel being given them by the inclination of the frame D, caused by the outer edge of said frame resting on one of the bars b of the carriage. When the carriage reaches the end of its movement, a beveled projection, a^x , on the carriage strikes the arm j of the

shaft L and detaches the pulley I from the shaft J, and the weight f draws back the carriage to its original position over the platform or frame P. The frame D is then turned, so that its outer edge will rest on the other bar b of the carriage, and the platform B is then elevated. The staves in the frame D are then released by throwing outward the clamp E, and the unjointed edges of the staves drop and rest on the platform, which causes them all to be brought to a level or in line with each other, however much the staves may vary in width. This reversing of the position of the frame D gives a reverse bevel to the two edges of the staves, and this bevel may be varied or modified by adjusting the stops p of the platform P. The platform P is then allowed to drop, the pulley I connected with shaft J, and the carriage is drawn again over

the cutter-head and the other edges of the staves jointed.

I claim as new and desire to secure by Letters Patent—

1. The reversible frame D, placed within the carriage C, in connection with the platform or frame P and cutter-head or disk N, when constructed and operating substantially as and for the purpose specified.

2. The concave ways or guides B B, in connection with the cutter-head or disk N, carriage C, with reversible frame D, and the platform or frame P, all arranged to operate substantially as and for the purpose set forth.

JOHN S. THOMPSON.
